(57) **CLAIM**

The ornamental design for an industrial faucet, as shown and described.

DESCRIPTION

FIG. 1 is an isometric view of an industrial faucet showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is a bottom perspective view thereof showing my design.

The broken lines in FIG. 1 show environmental structure and form no part of the claimed design. The broken lines in the rest of the figures depict elements of the industrial faucet that form no part of the claimed design.
